UNITED STATES PATENT OFFICE.

HORACE B. GALE, OF SAN FRANCISCO, CALIFORNIA.

ELEVATOR CONTROLLING DEVICE.

SPECIFICATION forming part of Letters Patent No. 510,638, dated December 12, 1893.

Application filed January 16, 1893. Serial No. 458,499. (No model.)

To all whom it may concern:

Be it known that I, HORACE B. GALE, a citizen of the United States, residing in the city and county of San Francisco and State of California, have invented certain new and useful Improvements in Elevator Controlling Devices, of which the following is a specification, reference being had to the drawings accompanying and forming a part of the same.

My invention relates especially to that class of elevator machinery in which the car is moved, directly or through intervening devices, by a piston or ram propelled by the combined pressure of a liquid, as water, and an elastic fluid, as steam; but it is also applicable to elevators operated entirely by hydraulic pressure. The movable body upon which the fluid pressure acts to raise or lower the car will be hereinafter referred to as a piston, it being understood that the devices herein claimed are equally applicable in case the car is propelled by a plunger or ram.

In the class of elevators to which my improvements relate, the up and down movements of the car are accompanied, respectively, by a flow of water back and forth through a valve, or valves, by closing which the car is stopped and held in any desired position. When the operating piston is propelled by the combined action of water and steam, the valves are preferably so designed that they can be set to permit the water to flow only in a determined direction, depending upon which way it is desired to move the car, thus preventing any momentary reverse movement at starting. My invention is designed to embody this feature, and has for its further objects, to provide improved means for easily operating the water-valves; to prevent violent shocks, such as may be produced by the too sudden closing of the water-valves heretofore used; and to provide improved means for automatically stopping the motion of the car at the ends of its travel.

The devices constituting my invention are represented in the accompanying drawings, in which—

Figure 1 is a general view of the apparatus applied to a "hydro-steam" elevator, illustrating means by which the controlling valves may be operated from the elevator car, and automatically by the piston rod. Fig. 2 is a

vertical section through the valve-casing transverse to the axis of the water-passage, showing the principles of construction of the valves. Fig. 3 is a section of the valve-casing on the line *s-s* of Fig. 2; and Fig. 4 shows an alternative arrangement of valves which may be used. The drawings are diagrammatic in form, the small parts being disproportionately enlarged for the sake of clearness.

The same letters of reference indicate corresponding parts in all the views.

Referring to Fig. 1, A is the operating cylinder, B the piston rod, carrying at its outer end the sheaves C, around which are passed the ropes D, by means of which the car E is raised and lowered. F is the steam receiver, containing a certain amount of water, and connected with one end of the operating cylinder A through the water passage G, of which the casing of the main water-valves H forms a part. I indicates the steam supply pipe, J the main exhaust pipe, and K the casing of the main steam-valves, by which steam may be admitted to and exhausted from the upper end of the receiver F.

The construction and arrangement of the water-valves and other controlling devices herein claimed are not affected by the design of the steam valves K, and the latter may be arranged to admit steam either to the receiver F, as shown, or to the farther end of the cylinder A, or to both receiver and cylinder, according to any of the methods used for operating elevators of this class.

L indicates an auxiliary-steam valve, by operating which the movements of the main water-valves are controlled, as will be herein-after explained. The auxiliary valve L is operated by the handle M in the elevator car through the ropes N, wheels O and P, the rope or chain Q, and wheel R, the same movement of the handles serving to operate the steam valves K through the wheel S, chain T, and wheel U. Any other of the known devices for operating the wheels R and U from the elevator car may be substituted for that here represented, and, if desired, the axis of the auxiliary valve L may be made to coincide with that of the wheel U, and both sets of steam-valves may be operated by the single chain T.

The design of the water-valves and the

means for operating them are shown in detail in Figs. 2, 3, and 4, the devices shown in these figures constituting the elements of my invention which are claimed as new.

5 The water-valves which have been heretofore employed in elevators of this class have been either positively-closing stop valves, or a combination of stop and check valves. The former if used alone are liable to the objection that when opened they permit a motion of the water in either direction, so that the car is subject sometimes to a momentary movement in the wrong direction at starting. The combination stop and check valves over-
10 come this defect; but they, as well as the plain stop valves, are liable to the objection that sudden closing of the valve, when the elevator is moving rapidly, instantly and positively stops the motion. This not only may
15 subject the occupants of the car to an unpleasant shock, but the sudden checking of the momentum of the water and of the moving car subjects the apparatus to a strain many times greater than it would otherwise
20 have to withstand.
25

The device by which I have overcome both of the defects above cited consists essentially of a pair of puppet valves, or check-valves, placed side by side in the water-passage, and
30 opening opposite ways relatively to the direction of flow through the passage, combined with means by which the external force holding either of these valves to its seat may be increased or diminished at will by the operator in the elevator car.
35

The check-valves may be pressed to their seats by the familiar device of weights or springs, and mechanical means employed for raising the weight, or releasing the spring
40 when it is desired to relieve the pressure on either valve in order to allow it to open. The means by which I prefer to control the pressure on the valves, however, is illustrated in Fig. 2, in which *a* and *b* represent the main
45 valves, resting upon the seats *c* and *d*.

Fig. 3 illustrates the arrangement of the valve-casing *H*, which is such that a pressure of the water in the passage *G* in the direction of the arrow tends to lift the valve *a*, while a
50 pressure in the contrary direction would tend to lift the valve *b*, the opening of either valve permitting the water to flow through the passage *G*.

To the outer ends of the valve stems are
55 attached pistons *e* and *f*, working in cylinders *i* and *j*, which are connected through the pipes *k* and *m* with the casing of the auxiliary valve *L*. Thence the pipe *n* leads to the source of steam, or other fluid employed in
60 working the elevator, and the pipe *o* to the atmosphere or to some receptacle for exhaust steam. The pipes *p* and *q* are intended to drain the water of condensation from the cylinders and steam passages, and may be connected to a steam trap, or other device for discharging the water.
65

It will be seen that when the valve *L* is in the position shown in the drawings the steam will pass from *n* through the valve *L* and pipes *k* and *m* into both the cylinders, *i* and *j*, and
70 will press upon the pistons *e* and *f*, holding the valves *a* and *b* to their seats with a force dependent upon the steam pressure and the area of the pistons *e* and *f*. By properly proportioning this area in relation to the pressure,
75 the valves may be held closed against any force ordinarily applied to operate the elevator. They are never closed absolutely, however, but only with a certain force, and will yield automatically to any momentary
80 abnormal pressure in either direction such as may be occasioned by the suddenly checked momentum of moving masses, thus serving as safety valves to protect the water passages, cylinder, piston, and supporting ropes from
85 undue strains. If now it is desired, for example, to lower the car, the handle *M* (Fig. 1) is moved so as to rotate valve *L* in the direction of the arrow, bringing it to the position shown by dotted lines in Fig. 2. This puts the upper
90 part of the cylinder *i* in connection with the exhaust passage *o*, thus relieving pressure on the valve piston *e*, but leaving the cylinder *j* in connection with the steam. The same movement of the handle *M* sets the main steam-
95 valves *K* (Fig. 1) so as to exhaust the steam from the receiver *F*. The pressure in the receiver being thus relieved, the weight of the car, acting through the ropes *D* and piston-
100 rod *B*, tends to force the water from the main cylinder *A* into the receiver *F*, traversing the passage *G* in the direction of the arrow in Fig. 3. The valve *a*, being no longer held to its seat by the pressure of steam on the piston *e*, is lifted by the water, thus opening the
105 passage *G* and permitting the car to descend. For an instant after operating the steam valves *K* as described, before the steam has had time to escape from the receiver *F*, there may be a tendency of the water to flow from
110 the receiver to the cylinder *A*, in the direction which would raise the car. But this momentary tendency to move in the wrong direction cannot take effect, as the valve *a* can be lifted only by a flow in the direction of the
115 arrow, while the valve *b* is held closed by the steam pressure on the piston *f*.

To stop the car, after it is in motion, the lever *M* is brought back to the middle of its stroke, returning the auxiliary valve *L* to its original position, when steam again enters the cylinder *i*, and forces the valve *a* to its seat. It is impossible, however, to close the valve in this way with sufficient suddenness to produce a shock, as the pressure of the
120 water under the closing valve *a* can never rise above a definite amount, namely, that required to balance the steam pressure on the area of the piston *e*. The force applied to stop the elevator therefore cannot exceed a
125 determined limit, no matter how quickly the valves *K* and *L* are shifted, and acts simi-
130

larly to a brake, always bringing the elevator to rest easily, without shock or excessive strain upon the mechanism.

It is evident that to set the water-valves so as to permit the raising of the car, it is only necessary to rotate the auxiliary valve L in the direction opposed to the arrow in Fig. 2, thus relieving the pressure on the check-valve b, and enabling the water to raise it and flow through the passage G in the contrary direction to the arrow of Fig. 3.

The auxiliary steam-valve L has the advantage of being very small and easily operated compared to the main water-valves, and may be placed at any desire distance from them by extending the pipes k and m.

V and W represent supplemental steam valves which are operated by the lug X connected to the main piston-rod B (Fig. 1). The lug X strikes the tappet, Y or Z, when the car has reached the top or bottom of its travel, which sets the corresponding supplemental valve W or V so as to admit steam to the valve-cylinder j or i and close the main water-valve, thus stopping the car. For example, suppose the auxiliary valve L to be set according to the dotted lines in Fig. 2, so as to connect the cylinder i with the exhaust passage o, the valve piston e and valve a being raised, and the car moving downward. Just before the car reaches the end of its travel, the lug X strikes the tappet Z, attached to the rod r, and turns the supplemental valve V in the direction of the arrow in Fig. 2, into the position shown by dotted lines in that figure. This closes the passage between the cylinder i and the auxiliary valve L, and admits steam to the cylinder i through the by-pass pipe t, thus closing the valve a and bringing the car to rest. The valve piston f and valve b are however still under the control of the valve L, so that the car can be started upward at pleasure. Whenever this is done, the lug X releases the tappet Z, and the valve V is returned to its normal position as shown by the weight u, a spring, or equivalent means.

It will be evident that instead of placing the two oppositely opening check-valves a and b, side by side in the passage G, they may be placed in series, as shown in Fig. 4, and held to their seats only by gravity, or by light springs. In this case, to allow the car to move, it is necessary to raise one of the check-valves, (either by an auxiliary steam-valve L admitting steam to a piston connected to the said check-valve, as shown, or by equivalent means controlled from the elevator car) leaving the water free to flow in the direction permitted by the other check-valve. The auxiliary valve L in Fig. 4 is the same in construction and operation as in Fig. 2, except that the steam and exhaust connections n and o are reversed.

The parallel arrangement of the valves is preferred to the series arrangement, as the latter is liable to cause shocks in closing.

Air, water, or any other convenient working fluid may of course be substituted for steam in working the valve pistons e and f, if preferred.

Having now shown that the details of construction and arrangement of parts in the apparatus which has been described are capable of considerable variations, I do not confine my claims to the specific forms shown and described; but

What I claim as my invention, and desire to secure by Letters Patent, is—

1. In an elevator controlling mechanism, the combination of the operating cylinder, a passage or conduit through which water or other liquid is admitted thereto and discharged therefrom; the oppositely acting check-valves arranged in said passage, each of which is opened by a flow in one direction only, being automatically closed against a contrary flow by the pressure of the liquid upon its back, independently of the controlling mechanism, and mechanism operated by ropes, pulleys, or other connections from the elevator car, by means of which the external closing force applied to each check-valve is varied independently by an operator in the car, substantially as described.

2. In an elevator controlling mechanism, the combination of the operating cylinder, a passage or conduit through which water or other liquid is admitted thereto and discharged therefrom, two oppositely-acting check valves placed in said passage, one of which may be opened by a flow only in one direction, while the other may be opened by a flow only in the contrary direction, an auxiliary valve or valves, and passages by which steam or other working fluid may be admitted to operate upon said check valves, means connecting said auxiliary valve with the elevator car whereby the former may be varied by an operator on the car and supplemental valves for governing the admission of steam or other fluid to the check valves independently, substantially as described.

3. The combination, in an elevator controlling mechanism, of two oppositely-acting check-valves in the passage through which water is admitted to and discharged from the operating cylinder, each valve being capable of being opened by a flow in one direction only; pistons connected to the valve-stems working in suitable cylinders, an auxiliary valve, or valves, and passages by which steam or other working fluid may be admitted to and discharged from these cylinders, means for operating the said auxiliary valve or valves from the elevator car, and a steam receiver and its valve, substantially as set forth and for the purpose described.

4. The combination in an elevator controlling mechanism of two oppositely acting check-valves with connected pistons and cylinders, as described, supplemental valves governing the admission of steam or other fluid

to each of said cylinders independently, and rods and tappets, or equivalent means, by which said supplemental valves may be operated automatically by the mechanism, so as 5 to stop the car at determined points of its movement, substantially as set forth.

5. In an elevator controlling mechanism, the combination of an operating cylinder, a passage through which water or other liquid 10 is admitted to and discharged therefrom, two oppositely acting check valves in said passage, each valve being capable of being opened by a flow in one direction only, pistons connected to the valve stems working in suitable 15 cylinders, an auxiliary valve or valves and passages by which steam or other working fluid may be admitted to and discharged from these cylinders, means for operating the said auxiliary valve or valves from the elevator 20 car, and supplemental valves governing the admission of steam or other fluid to each of said cylinders independently, together with automatically-operating mechanism connected with the operating cylinder whereby these 25 supplemental valves are automatically operated so as to stop the car at determined points of its movement, substantially as described.

6. In an elevator controlling mechanism, the combination of two oppositely acting 30 check valves with connected pistons and cylinders as described, supplemental valves governing the admission of steam or other fluid to each of said cylinders independently, automatically operated mechanism connected 35 with the operating cylinder by which said

supplemental valves are automatically operated, an auxiliary valve operated through connections with the elevator car and a receiver for steam or other fluid, together with a steam valve, which valve is operated jointly with 40 the auxiliary valve by means of the same mechanism, substantially as described.

7. In an elevator controlling mechanism, the combination of two oppositely-acting 45 check valves in the passage through which water is admitted to and discharged from the operating cylinder, each valve capable of being opened by the flow in one direction only, pistons connected to said valve-stems, suitable cylinders in which said pistons are located and within which they work, steam passages connecting with each of said cylinders, a valve in said passage which is operated from the elevator car by suitable mechanism arranged for the purpose, supplemental valves 50 located in the same passage with the auxiliary valves on opposite sides thereof, and mechanism consisting of rods and tappets, arranged to be operated by the mechanism of the operating cylinder so that the supplemental valves may be automatically actuated, substantially as described.

In testimony whereof I have hereunto affixed my signature in the presence of two witnesses.

HORACE B. GALE.
